UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

SPRING-HINGE.

SPECIFICATION forming part of Letters Patent No. 747,276, dated December 15, 1903.

Application filed October 1, 1903. Serial No. 175,310. (No model.)

To all whom it may concern:

Be it known that I, HENRY TSCHERNING, a citizen of the United States of America, residing at Freeport, in the county of Stephenson 5 and State of Illinois, have invented certain new and useful Improvements in Spring-Hinges, of which the following is a specification.

My invention relates to certain improvements in spring-hinges, relating particularly to an improved method of fastening the spring upon one of the leaves of the hinge.

The invention is illustrated in the drawings by means of four figures, of which—

15 Fig. 1 is a face view of the spring-hinge. Fig. 2 is an edge view of the same. Fig. 3 is a horizontal view looking downward upon the plane 3 3 of Fig. 1, and Fig. 4 is a horizontal section looking down upon the plane 4 4 of Fig. 1.

A is one of the leaves of the hinge, and B the other. These leaves are provided with knuckles a a' b b', which are pivoted together by means of rivets C C'. The leaf B has a 25 tongue b², provided with a perforation b³ and extending toward the leaf A. The leaf A is provided with a transverse socket a² upon the outer edge of the leaf and a longitudinal socket a³ upon the inner edge of the leaf. A 30 spring D is composed of a coil d, from the side of which opposite the pivot-line of the hinge extends upwardly an arm d, the upper end of which is connected, by means of a link E, to the tongue b², the link being secured in

35 the perforation b³ of said tongue. From the other side of the coil d extends an arm d², which passes through the socket a³ and is thereafter bent to extend outward across the leaf and into the socket a².

The hinge-leaves are preferably made of 40 sheet metal, the socket a² being preferably formed by stamping it up from the body of the leaf and the socket a³ being preferably formed from a tongue upon the inner edge of the leaf by bending the same upward and 45 around the arm of the spring. This method of fastening provides a secure means for holding the spring upon the leaf against any tendency to move therefrom caused by the operation of the hinge. 50

I claim as new and desire to secure by Letters Patent—

In a spring-hinge, the combination with the pivoted leaves, one of which has a tongue upon the inner edge near one end extending 55 toward the other leaf and the other of which has a longitudinal socket along its inner edge near its middle portion and a transverse socket upon its outer edge near one end of the longitudinal socket, of a spring having a coil 60 arranged near the end of one of the leaves, an arm extending longitudinally of the hinge from said coil through the inner socket, and afterward transversely through the outer socket and an arm upon the other side extending 65 longitudinally of the hinge toward the other end thereof and a link connecting the end of the latter arm with the tongue upon the other leaf.

In witness whereof I have signed the above 70 application for Letters Patent, at Freeport, in the county of Stephenson and State of Illinois, this 25th day of September, A. D. 1903.

HENRY TSCHERNING.
